Primary Examiner — Selina Sikder

(74) Attorney, Agent, or Firm — Winthrop & Weinstine

(57) **CLAIM**

The ornamental design for a control holder, as shown.

DESCRIPTION

FIG. 1 is a perspective view of the control holder showing our new design;

FIG. 2 is a left side view of the control holder of FIG. 1;

FIG. 3 is a right side view of the control holder of FIG. 1;

FIG. 4 is a back view of the control holder of FIG. 1;

FIG. 5 is a front view of the control holder of FIG. 1;

FIG. 6 is a top view of the control holder of FIG. 1; and,

FIG. 7 is a bottom view of the control holder of FIG. 1.

1 Claim, 7 Drawing Sheets
